CLAIM

The ornamental design for a bottle, as shown and described.

DESCRIPTION

FIG. 1 is a top, right side perspective view of the bottle of FIG. 7 shown with an unclaimed lid portion;

FIG. 2 is a rear elevational view thereof;

FIG. 3 is a right side elevational view thereof, the left side elevational view being a mirror image;

FIG. 4 is a front elevational view thereof;

FIG. 5 is a top plan view thereof;

FIG. 6 is a bottom plan view thereof;

FIG. 7 is a top front, right side perspective view of a bottle of the present invention;

FIG. 8 is a rear elevational view thereof;

FIG. 9 is a right side elevational view thereof, the left side elevational view being a mirror image;

FIG. 10 is a front elevational view thereof;

FIG. 11 is a top plan view thereof; and,

FIG. 12 is a bottom plan view thereof.

The broken lines shown in the drawings are for illustrative purposes only and form no part of the claimed design.
